UNITED STATES PATENT OFFICE.

MINNIE MAY DAWSON, OF MONACA, PENNSYLVANIA.

GAME APPARATUS.

1,147,218.

Specification of Letters Patent. Patented July 20, 1915.

Application filed December 9, 1914. Serial No. 876,210.

To all whom it may concern:

Be it known that I, MINNIE MAY DAWSON, a citizen of the United States of America, residing at Monaca, in the county of Beaver and State of Pennsylvania, have invented certain new and useful Improvements in Game Apparatus, of which the following is a specification, reference being had therein to the accompanying drawing.

10 This invention relates to game apparatus and has for its object to provide a device of such class, in a manner as hereinafter set forth, whereby a new and novel game can be played and which will cause considerable amusement. The game primarily is called "parlor keno."

Further objects of the invention are to provide a game apparatus which is simple in its construction and arrangement, durable, and inexpensive to manufacture.

With the foregoing and other objects in view the invention consists of the novel construction, combination and arrangement of parts as hereinafter more specifically described and illustrated in the accompanying drawings wherein is shown an embodiment of the invention, but it is to be understood that changes, variations and modifications can be resorted to which come within the scope of the claim hereunto appended.

Figure 1 in the drawing illustrates in plan a game apparatus in accordance with this invention. Fig. 2 is a side elevation of the game-board showing the arches and one 35 of the stakes. Fig. 3 illustrates an ordinary pair of dice used in playing the game.

Referring to the drawings in detail 1 denotes a base, preferably square, and which has its upper face provided with printed, 40 stamped or similar means to constitute courses 2, 3, 4 and 5 and each of said courses are divided into squares. The courses 2 to 5 are arranged upon the marginal portion of the upper face of the base and said course 45 2 is connected to the course 3 by turn 6, formed of triangular shaped spaces. The course 3 is connected to the course 4 by turn 7 formed of triangular shaped spaces, and the course 4 is connected to the course 5 by 50 a turn 8 formed of triangular-shaped spaces. And the course 5 is connected to the course 2 by a turn 9 formed of triangular shaped spaces.

Leading from the turns 6, 7, 8, and 9 are 55 radially disposed courses 10, 11, 12 and 13 and each of said radially disposed courses

terminates in one corner of a square course 14. The radially disposed courses 10-13 are formed of square spaces and the square course 14, which is arranged at the center 60 of the base 1, is formed of square spaces. Arranged at the entrance of each of the radially disposed courses 10 to 13 is an arch 15, and arranged between the square courses 14 is a pair of arches 16. Located within the outer square is a square composed of paths 30, 31, 32 and 33, which are marked into squares similarly to the outer paths. Leading to the course 2 is a path 17, which 65 extends from a starting square 18, the latter being provided with a peg 19. Leading to the course 4 is a path 20, which extends from a starting square 21, having a peg 22. The path 20 is provided with an arch 23 and the path 17 with an arch 24. They are 70 all formed of wire and have the ends embedded in the top of the board. The paths 14 are provided with double arches 25, 26, 27 and 28. Associated with the courses will be a series of shiftable members and one of 75 which is indicated at 29.

The manner of playing the game is as follows: It takes from two to six people, or more. Throwing the dice it takes a five to go through the first arch, which is either 80 arch 23 or 24. Assuming that two people are playing, the men 29 are started from opposite sides of the board. When you go through an arch you have the chance of throwing the dice again. After you are 85 through the arches, throwing the dice again you count the numbers on the dice and move along the men that number. In case you cannot use all the numbers on the dice, use the larger number on a single dice and move 90 that many. The other party coming out on the same block as you are, when throwing the dice, she can send you back as many blocks as numbers on the dice, if possible or go forward. Two persons on the same block 95 cannot pass until one moves forward. Going through the double arch it takes a five as through the single arch. Assuming that the man starts at 21, it travels to corner 8, passes up path 12 and goes around paths 100 33, 30, 31 and 32 in order. It then goes down to corner 8 on path 12 and travels over path 5 and up 13 and around path 14. It then comes down path 13 again and passes on path 1 to arch 24 where after passing 105 through the arch it takes the throw of five on the dice to hit peg 19. The same ground

110

on the opposite side of the board is covered by the man starting from 18 and he in turn hits peg 22. The man then starts back home over the same route his opponent has traveled. The first man getting back to where he started wins the game after hitting the peg. In playing partners you play the same as single except when going through the arches, your partner being in position with you, throwing two fives you can take her through the arch with you. The opposite party meeting on the same block with you, after going through the arch, can be sent back as many numbers on the dice, or you 15 can use all the numbers to move forward yourself if possible.

What I claim is:—

A game apparatus comprising a base having the top face thereof marked to con-

stitute a series of courses, and further having means to constitute turns connecting said courses to said base, and further having means to constitute square courses, and radially disposed courses leading from said turns to the square courses, and an arch at 25 the outer end of each of said radially disposed courses, arches located on the inner courses and means to provide a pair of starting spaces connected with certain of said first mentioned courses, and a peg arranged at each starting space.

In testimony whereof I affix my signature in the presence of two witnesses.

Miss MINNIE MAY DAWSON.
